DESIGN FOR A LIPSTICK HOLDER OR SIMILAR ARTICLE

Michael Graboi, New York, N. Y.

Application October 19, 1945, Serial No. 122,992

Term of patent 3½ years

(Cl. D86—10)

To all whom it may concern:

Be it known that I, Michael Graboi, a citizen of no country and resident of New York, in the county of New York and State of New York, have invented a new, original, and ornamental Design for a Lipstick Holder or Similar Article, of which the following is a specification, reference being had to the accompanying drawing, forming a part thereof, and of which

Figure 1 is a front view of a lipstick holder or similar article showing my new design; Fig. 2 is a side view thereof; and Fig. 3 is a bottom view thereof.

I claim:

The ornamental design for a lipstick holder or similar article, substantially as shown.

MICHAEL GRABOI.
